(57) **CLAIM**

We claim the ornamental design for a medicament delivery device, as shown and described.

DESCRIPTION

FIG. 1 is a top plan view of the claimed design;

FIG. 2 is a front elevation view thereof;

FIG. 3 is a right side elevation view thereof;

FIG. 4 is a bottom plan view thereof;

FIG. 5 is a bottom perspective view thereof; and,

FIG. 6 is a perspective view thereof.

The dash dot lines immediately adjacent to the claimed area represent the boundaries of the claimed design. The broken lines in the figures illustrate the portions of the design and environment that form no part of the claimed design. None of the broken lines form any part of the claimed design.
